UNITED STATES PATENT OFFICE.

ASHTON G. STEVENSON, OF CHICAGO, ILLINOIS, ASSIGNOR TO CHICAGO LINO-TABLER COMPANY, OF CHICAGO, ILLINOIS, A CORPORATION OF ILLINOIS.

RULED TYPE-FORM AND METHOD OF PRODUCING SAME.

1,168,602.

Specification of Letters Patent.

Patented Jan. 18, 1916.

Original application filed June 17, 1912, Serial No. 704,142. Divided and this application filed October 17, 1914. Serial No. 867,180.

To all whom it may concern:

Be it known that I, ASHTON G. STEVENSON, a citizen of the United States, and a resident of Chicago, Cook county, Illinois, 5 have invented certain new and useful Improvements in Ruled Type-Forms and Methods of Producing Same, of which the following is a specification.

My invention relates to ruled type forms 10 and has particular reference to an improved system of applying so called lino-tabler rules to type forms.

The object of my invention is to cheapen 15 the application of vertical rules to type forms; to eliminate the necessity for the use of special matrices in ruling type forms with ruling members adapted to be placed upon the upper flat surface of the form. This application being a division of my co- 20 pending application for patent on rule broach, Serial No. 704,142, filed June 17, 1912.

My invention consists in the improvements herein described and particularly 25 pointed out in the appended claims.

My invention will be more readily understood by reference to the accompanying drawings forming a part of this specification and in which:

30 Figure 1 is a perspective view of a ruled type form illustrating a preferred embodiment of my invention; Fig. 2 is an enlarged fragmentary vertical section of the type form on the line 2-2 of Fig. 1; Fig. 3 is a 35 vertical section on the line 3-3 of Fig. 2, the rule being removed from the form and shown in juxtaposition.

This present application is an improvement upon the method of ruling type forms 40 disclosed in United States Patent, Serial No. 974,718, issued to me November 1, 1910, and wherein the rule holding lugs are disclosed as being bendable over the inclined sides of the rule to hold the rule in position upon 45 the form. It is also an improvement upon the method of ruling type forms disclosed in United States Patent No. 1,049,165, issued to me Dec. 31, 1912, and wherein rigid lugs are provided upon the upper surface of linotype 50 slugs between which the rule is adapted to be clamped when the form is locked in a chase.

This present application relates particu-

larly to the method of ruling type forms with rules which are of a height adapted to 55 be placed upon the level top surface of type forms built up of linotype slugs having openings produced in rigid projections rising from this level top surface said openings having inwardly inclined or overhanging 60 walls. In other words said slugs are provided with openings between rigid lugs, the tops of which openings are contracted and which are adapted to receive and retain rules the lower parts or bases of which 65 are wider than their printing edges. In fact this present application refers particularly to the method of ruling type forms wherein so called linotype rules are held upon the upper flat surface of type forms by means of 70 rigid overhanging rule holding projections.

In said drawings A represents a type form made up of a plurality of linotype slugs B each of which has an upper top surface b^1 which is relatively near to the printing surface of the form, and the combined top surfaces of all the slugs make up the level top surface of the form upon which the rules are supported. Some of these slugs are provided with printing projections b^2 80 adapted to print lines and some are provided with non printing projections b^3 and b^4 which do not rise to the printing surface of the form but each of these several projections whether printing or non printing are 85 provided with rule receiving openings b^5 to receive the lino-tabler rules C. The rule C is preferably of a triangular shape as shown, the upper edge c^1 being adapted to print a line and being relatively narrow, the base c^2 90 of the rule being relatively broad and the sides c^3 being inclined. That is the sides are outwardly flared and this rule is adapted to be held in position upon the upper level top surface of the form by the overhanging sides 95 b^6 of the rule receiving openings b^5 . The projections which are provided with the rule receiving openings as shown may have different shapes depending upon the means by which they are formed but whatever shape 100 these projections have, the one characteristic which is common to them all is that each is pierced with a rule receiving opening having inwardly inclined sides and providing an opening which is narrower at its top 105 than at its base, the base thereof being sub-

stantially in the plane of the level top surface of the form.

In practising my method of ruling type forms I provide slugs which have rule receiving openings suitably spaced to receive the desired number of rules or to receive rules which may be placed in desired relation to the printing type carried by the slugs. That is the form is provided with the rule receiving openings spaced to produce the desired effect and after the several slugs are arranged in position with the rule receiving openings in alinement the rules are pushed endwise into position upon the form and are retained in position by the overhanging side walls of the several rule receiving openings provided in the projections which rise above the level top surface of the form.

Having thus described my invention I claim as new and desire to secure by Letters Patent:

1. A ruled type form, which comprises a plurality of lino-type slugs, certain of which are provided with longitudinally disposed type-high ribs and others of which are provided with less than type-high integral projections, separable printing rules disposed at right angles to said rigid integral ribs and projections, and held in openings provided therefor in said ribs and projections, the side walls of said openings overhanging the bases of the rules.

2. A ruled type form which comprises a plurality of associated printing slugs in combination with interposed slugs having integral longitudinal printing ribs on their upper edges, other interposed slugs which have less than type height ribs on their upper edges, and separable line printing rules arranged at right angles to the longitudinal printing ribs and held in transverse openings provided therefor in said printing and non-printing ribs, the side walls of said openings overhanging the bases of the rules.

45. 3. A quad-high slug having a longitudinal

rib on its upper edge, the upper surface of the rib being adapted to be below the printing surface of the type form in which the slug is used said rib being provided with transverse holes to receive a lino-tablet rule, 50 the walls of said opening projecting over the base of the rule.

4. A quad-high linotype slug having a longitudinal rib on its upper edge the combined height of the slug and rib being less than 55 type height, said rib being provided with transverse openings adapted to receive and to hold lino-tablet rules.

5. A quad-high linotype slug having a longitudinal rib on its upper edge, the combined 60 height of the slug and rib being less than type height, said rib being provided with transverse openings extending from its upper edge to its base and said openings being constricted at their upper edges to hold lino-tablet rules. 65

6. A linotype printing slug provided with a rigid projection on its upper edge, said projection having a transverse opening adapted to receive and to hold a printing 70 rule of triangular cross section, the sides of the opening projecting over the inclined sides of the rule, as and for the purpose specified.

7. A system of ruling type forms which 75 comprises the combination with two slugs of a ruling member of less than type height and having a base which is wider than its printing edge, the slugs being provided with openings between rigid projections to receive 80 the printing member, the side walls of the openings projecting over the base of the rule as and for the purpose specified.

In testimony whereof, I have hereunto set my hand this 23rd day of September, 1914, 85 in the presence of two subscribing witnesses.

ASHTON G. STEVENSON.
